MEASURING AND DISPENSING CAN

Earl C. Akers, Detroit, Mich., assignor of one-half
to Frank L. McLaughlin, Detroit, Mich.

Application March 19, 1934, Serial No. 716,241

6 Claims. (Cl. 221—98)

This invention relates to liquid receptacles, and is particularly directed to the provision in conjunction with oil receptacles and the like of novel fractional dispensing means for limiting to a de-

5 sired amount the portion of its fluid contents which may be withdrawn from a container at a single pouring, thereby enabling positive se-
10 curance of a predetermined quantity only, re-
gardless of the capacity of the container, at every
10 pouring.

An important object of my invention is to pro-
15 vide a container especially suitable for motor oil, and of such nature that motorists and other
15 users of oil in relatively small quantities, but
who nevertheless purchase it in greater amounts
20 than they ordinarily use at one time, may pour
oil directly from a container holding perhaps sev-
eral quarts or more into the crank-case or other
25 part to be lubricated, and yet obtain only a de-
sired quantity, as for example one quart, at each
20 pouring. At present it is the usual practice to
measure out the desired quantity into a separate
measure before pouring it into the crankcase.
This practice is not only bothersome in itself, but
25 the necessity of keeping the measure, and usual-
ly a funnel as well, accessible (and clean, if the
introduction of grit into the motor is to be avoid-
ed) is such a nuisance as to discourage many
30 from buying oil in quantities despite the marked
economy which may be thus effected.

The elimination of these troublesome disad-
35 vantages and drawbacks, and provision of an
improved and simplified container adapted to
hold a suitable quantity, as for example several
35 quarts, of oil or other liquid, yet from which its
contents may be poured a quart at a time only, is
a primary object of this invention, together with
such simplification of the means for accom-
40 plishing these desirable results that incorporating my
invention adds very little to the cost of manu-
facture of a container.

Other objects and advantages will be apparent
45 from the following description, wherein reference
is made to the accompanying drawing illustrating
preferred embodiments of my invention, and
wherein similar reference numerals designate
similar parts throughout the several views.

In the drawing:

Figure 1 is a plan view of an oil can of a well
50 known eight-quart variety insofar as its general
construction is concerned, but which is equipped
with measuring means in accordance with the
principles of my invention.

Figure 2 is a vertical section taken substan-
55 tially on the line 2—2 of Figure 1 and looking in
the direction of the arrows.

Figure 3 is a similar vertical section showing
the container in tilted, fluid-delivery position, the
disposition of oil therewithin under typical con-
60 ditions being also indicated in dotted lines, and

Figure 4 is a perspective of the overweighted
valve member employed to regulate communica-
tion between the two fluid chambers of the re-
ceptacle.

Referring now to the drawing, the interior of
the container, as shown in Figure 2, may be di-
vided into two compartments by the wall or par-
tition A, which forms a false bottom, the space
beneath which (designated D) defines a measur-
ing chamber whose capacity is of course fixed by
10 the positioning of the wall, which is preferably
provided with downturned flanges, as B, adapted
to support it in desired spaced relation with re-
spect to the bottom of the can. The flanged wall
assembly A—B is proportioned to fit slidably but
15 relatively tightly inside the can, and may be held
in place entirely by friction. Any slight leakage
which takes place because of such method of
inserting the partition is of course immaterial,
since only approximate apportionment of the
20 contents into quart or other desired units is re-
quired. The space above the partition, desig-
nated C, constitutes the main storage chamber
and communicates with the measuring chamber
D through an aperture E. Through this aper-
25 ture, when the valve L (presently to be described)
is open, fluid from the upper chamber C may
freely flow by gravity into the measuring chamber
D. Near one corner of the container rises a de-
livery or pouring tube G connecting the measur-
30 ing chamber with the pouring cap opening P.
Through this the fluid, which has filled the cham-
ber D when the container is in the upright posi-
tion shown in Figure 2, may be poured directly to
a desired point.

When the container is upright the over-
35 weighted portion J of the valve-carrying support
H forces upwardly and holds in raised position the
opposite, active portion of the valve-carrying
piece, which is pivoted on a pin K supported by
40 the partition A appurtenant the valve opening E.
The underside of the valve member H carries a
valve portion L of suitable relatively resilient ma-
terial, such as cork, movable upon swinging the
valve member to stop and free the valve opening.

When the container is upright, as above indi-
45 cated, the weight J overbalances the valve section,
so that the latter is then distinctly raised from
closure position with respect to aperture E.
When the receptacle is tilted to the oblique posi-
50 tion shown in Figure 3, the center of gravity of
the weighted valve support passes over the center
of pivot pin K, so that the valve is then urged to-
ward closed position to block the communicating
aperture E. Thus when the can is tilted for pour-
55 ing the valve is closed, permitting all of the fluid
contained in the measuring chamber D to be
poured through the delivery tube G and from the
receptacle, without the possibility of any more of
the fluid still contained in the upper storage 60

chamber C making its way into the lower measuring chamber. If, for example, the container has a total capacity of eight quarts, while the measuring chamber holds one quart, pouring from the can in the normal way enables the user to pour out only the quart contained in the measuring chamber, and no more, upon a single tilting of the can. When, however, the receptacle is again restored to upright position, the weight J 10 opens the valve and oil again fills the measuring chamber to enable repetition of the measured pouring thereafter.

A breather vent, as M, may be provided in the partition A to break any tendency toward creation of a vacuum in the measuring chamber. This vent is preferably arranged close to the corner diagonally opposite the pouring tube G, and a vent as N is also arranged in the top of the can and closable by means of a cap as N'.

Oil cans of this variety are ordinarily not filled completely to the top, and it will be apparent that the can may be tilted to a sharp angle when pouring, so that the measuring chamber is substantially vertical, if desired. As a result, the surface 20 of the oil then lies below both vents M—N, and air may enter the measuring chamber to replace the oil therein as the latter flows out. If through carelessness any slight amount of oil enters the measuring chamber through the small vent during pouring, the slight inaccuracy thereby induced is unimportant in view of the purpose for which the container is intended to be used.

Attention is also desired to be called to the inturned flanges Q with which the overbalanced valve supporting member H is provided. These will be seen to be so disposed that as the can is tilted (to the left as viewed in the drawing) the movement of the oil toward the low side of the container results in the striking of the valve, 30 inside the pocketed portion defined in the flanges Q and sheet metal body portion of the valve support H, by a quantity of the moving oil. The momentum of the moving oil thus helps to positively throw the valve toward closed position. As shown in Figure 3 a pouring funnel, as R, may be substituted for the cap P' during use of the can to assist in directing contained liquid into any desired receptacle, as oil into a breather pipe. The funnel shown is of a conventional variety adapted 40 to screw on the spout P in place of the cap.

While it will be apparent that the illustrated embodiments of my invention herein disclosed are well calculated to adequately fulfill the objects and advantages primarily stated, it is to be understood that the invention is susceptible to variation, modification and change within the spirit 50 and scope of the subjoined claims.

What I claim is:

1. A measuring and dispensing can having in combination with an apertured wall separating the interior thereof into a general fluid-storage space and a subjacent measuring space, a pouring outlet leading from said last-named space to the exterior of the can, and an overweighted valve member controlling the possible flow between the two spaces and lying in non-closing position with respect to the aperture in the interior wall when the can is in horizontal, non-pouring position, said valve member being adapted to be rocked to position of closure with respect to said aperture when the can is inclined from its normal horizontal position for pouring.

2. In combination with a plurally chambered

can having one of its chambers of a predetermined capacity and located subjacently to another chamber and in potential communication therewith, an overweighted valve member in normal position of non-closure with respect to the communication passage between the chambers, said valve being adapted to be moved by gravity into position of closure with respect to the passage between the chambers upon the inclination of the can as a whole from its normal position, 10 and a pouring spout leading from the measuring chamber to a point outside of the can.

3. In combination with a container, means enabling fractional dispensing of a predetermined portion only of the contents of the container upon a single inclination thereof from upright position, said means comprising a wall bounding a measuring chamber portion and having an opening therein providing communication between said measuring chamber and the remainder of the container, valving means for said opening, means responsive to movement of the container from upright position for moving said valving means to closed position, and an outlet 20 communicating with said measuring chamber. 25

4. In combination with a container, means enabling fractional dispensing of a predetermined portion only of the contents of the container upon a single inclination thereof from upright position, said fractional dispensing means including partitioning means defining a chambered section of predetermined capacity appurtenant to the bottom of the container and having an opening therein providing communication with other portions of the container, valving means for said opening for controlling such communication, means responsive to movement of the container out of upright position for actuating the valving means, and a breather connecting said chambered section with a point higher than the normal liquid level therein. 30

5. In combination with a container for a liquid, fractional dispensing means for limiting the proportion of contents of the container which may be poured therefrom by a single tilting thereof, 45 comprising a measuring chamber section appurtenant and in communication with the bottom portion of the container, valving means for such communication, means responsive to movement of the container out of upright position for actuating the valving means, and a pouring portion connected to said measuring chamber section and extending higher than the normal liquid level in the container. 50

6. In combination with a container for a liquid, 55 fractional dispensing means for limiting the proportion of contents of the container which may be poured therefrom by a single tilting thereof, comprising partitioning means defining a measuring chamber section and having an opening 60 therein providing communication with the bottom portion of the container, valving means for such opening, means responsive to movement of the container out of upright position for actuating the valving means, a pouring portion connected to said measuring section and extending higher than the normal liquid level in the container, the container having a breather opening therein, and the measuring chamber having a breather therein permitting communication between the measuring chamber and the first mentioned breather when the container is tilted. 70

EARL C. AKERS.
